(57) **CLAIM**

The ornamental design for a cosmetic product package, as shown and described.

DESCRIPTION

FIG. 1 is a front perspective view of a cosmetic product package embodying the present design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The figures include surface shading lines that merely clarify contours of various surfaces and does not indicate surface texture, material, or color.
